EMBROIDERED NARROW WOVEN FABRIC
TRIMMING OR SIMILAR ARTICLE

Milton Rosenbaum, New York, N. Y.

Application November 4, 1950, Serial No. 12,848

Term of patent 3½ years

(Cl. D92—1)

To all whom it may concern:

Be it known that I, Milton Rosenbaum, a citizen of the United States of America and a resident of the city of New York, county of Bronx, and State of New York, have invented a new, original, and ornamental Design for an Embroidered Narrow Woven Fabric Trimming or Similar Article, of which the following is a specification; reference being had to the accompanying drawing forming a part hereof.

In the drawing:

Fig. 1 is a plan view of an embroidered narrow woven fabric trimming or similar article, showing my new design; and

Fig. 2 is an edge view of the same;

Fig. 3 is a section on an enlarged scale taken on line 3—3 of Fig. 2.

I claim:

The ornamental design for an embroidered narrow woven fabric trimming or similar article, substantially as shown.

MILTON ROSENBAUM.
